UNITED STATES PATENT OFFICE.

JOHANN BROLICH, OF IPS, AUSTRIA-HUNGARY, ASSIGNOR TO ALBERT GANS, OF KEMMLBACH, AUSTRIA-HUNGARY.

BLOWING-FAN.

SPECIFICATION forming part of Letters Patent No. 609,571, dated August 23, 1898.

Application filed August 27, 1897. Serial No. 649,707. (No model.) Patented in Austria August 18, 1896, No. 46/3,222.

To all whom it may concern:

Be it known that I, JOHANN BROLICH, a subject of the Emperor of Austria-Hungary, residing at Ips, in the Province of Lower Austria, in the Empire of Austria-Hungary, have invented certain new and useful Improvements in Blowing-Fans, (patented in Austria August 18, 1896, No. 46/3,222,) of which the following is a specification.

This invention relates to blowing-fans with a movable case for directing currents of heated or dry air over surfaces which have to be dried, and has for its object to provide means for distributing the air-current over a large surface varying the width of the discharge-opening, and, further, providing special bearings for the fan-shaft and fan-case. For this purpose I make the fan-case with trunnions which work in parts of the axle-bearings, and I pass the axle freely through these trunnions and journal them in the parts of the bearings beyond the trunnions. From this fan-axle I drive by a reducing-gear at slow speed a crank or eccentric from which a rod extends to a pin on the fan-casing, so that when the fan revolves the casing is caused to oscillate to and fro on its axis, sending the air-current in various directions over a large surface. The pin to which the crank or eccentric rod is linked may be adjusted nearer to or farther from the axis, so that the extent of the oscillations of the casing may be made greater or less, as desired. By hinging one side of the discharge-mouth to the case and adjusting this side nearer to or farther from the fixed side the mouth can be narrowed or widened, as desired.

The improved fan is illustrated in the accompanying drawings, in which—

Figure 1 is a side view; and Fig. 2, an elevation, partly in section. Fig. 3 shows in section, on an enlarged scale, the device for varying the width of the discharge-opening. Fig. 4 is a front view of this device. Figs. 5 and 6 represent details of the trunnions and bearings.

As shown in the drawings, the fan *a* is provided with a surrounding case *b*. Further, there are trunnions or sockets *b' b'* on the case reaching into the hollowed-out portions *d'* in the bearings *d*, in which the shaft *c* rests.

The trunnions surround shaft *c*, but have larger openings than the bearing *d*, so that the case is mounted loosely on the shaft and moves independently from the revolving fan. 55

On the front side the case *b* carries a pin or bolt *f*, to which is linked a rod *g*. The second end of this rod is linked to a crank-wheel *h*. The wheel *h* is slowly and continually rotated from the counter-shaft *c'*, Fig. 1. 60 By this rotation the rod *g* is given a reciprocating motion by which the case *b* is oscillated about the shaft *c*. Owing to this oscillation the discharge-nozzle *b²* occupies different positions, sending the air-current in various directions over a large surface. Hereby the whole air receives a whirling motion and the heat is uniformly distributed, so that a swift drying is effected.

The bolt *f* may be preferably adjusted in 70 a slot *f'* of the case *b* in order to effect greater or less oscillations of the case.

In order to be able to adjust at will the width of the mouth, the one side *b³* of the mouth *b²* is hinged at *m*, so that it may be 75 placed nearer to or farther from the fixed side by means of linked screw-bolts *p* and nuts *p'*, counteracted by spring *n*.

For the purpose of diminishing the friction in the bearings of the case and of the shaft 80 the trunnions or sockets *b' b'* of the case have a somewhat larger diameter than the shaft *c*, so that the latter may freely pass.

The bearings *d d* have two openings or bores of a different diameter. The larger one, *d'*, 85 corresponds with the external diameter of the trunnions or sockets *b' b'*. The smaller one, *d²*, corresponds with the diameter of the shaft *c*, so that friction between trunnion *b' b'* and shaft *c* is prevented, even when they turn in 90 different directions.

It is obvious that these fans may be employed not only for drying-chambers, but also for other industries, and that the details of construction may be widely varied without 95 departing from the nature of this invention.

Having now described my invention, I claim as new and desire to secure by Letters Patent—

1. A blowing-fan consisting of the fan *a* 100 mounted on shaft *c* in bearings *d*, an oscillating fan-case with mouth *b²* and provided

with trunnions b' reaching into the hollowed-out portions d' of the bearings d and mounted loosely on shaft c , a reducing-gear, a crank-wheel h with a rod g which is linked to a bolt 5 f in slot f' on the case b so that upon revolving the fan the case oscillates, as specified.

2. In a blowing-fan an oscillating casing mounted loosely on the fan-shaft, a reducing-gear in connection with the shaft and driving 10 a crank-wheel with crank-rod which is linked to an adjustable bolt on the casing, substantially as specified.

3. In a blowing-fan an oscillating casing

mounted loosely on the fan-shaft and having a mouth, in combination with a device for varying the width of the mouth consisting of a hinged portion b^3 , a pivoted bolt p with nut p' , and spring n , as specified.

In testimony whereof I have signed this specification in presence of two subscribing 15 witnesses.

JOHANN BROLICH.
